UNITED STATES PATENT OFFICE.

WILLIAM F. COSTON, OF NEW YORK, N. Y.

DESIGN FOR A FLAG OR BANNER.

SPECIFICATION forming part of Design No. 30,976, dated June 13, 1899.

Application filed May 17, 1899. Serial No. 717,218. Term of patent 14 years.

To all whom it may concern:

Be it known that I, WILLIAM F. COSTON, a citizen of the United States, residing at New York, in the county of New York and State 5 of New York, have invented and produced a new and original Design for Flags or Banners, of which the following is a specification.

This invention relates to a design for a flag or banner; and it consists of the features and 10 characteristics hereinafter described.

Referring to the drawing, the figure is a representation of my design applied to a flag.

The leading features of the design consist of the stripe A, crossing the flag diagonally 15 and bearing a wheel B, surmounted by a spread-eagle C and crossed by a sword D and key E. The diagonal stripe is of a contrast-

ing color to the triangular ends F and G of the field, the end F being red, the other end blue, and the stripe white. The wheel contains thirteen spokes H, surrounded by a circle of thirteen stars I, arranged on the rim of the wheel. The spread-eagle surmounts the wheel between the upper ends, respectively, of the sword and key, which cross each other at or near the hub of the wheel.

Having thus described my invention, what I claim is—

The design for a flag or banner as herein shown and described.

WILLIAM F. COSTON.
